UNITED STATES PATENT OFFICE.

HALE E. HAWK, OF KANSAS CITY, MISSOURI.

DREDGING OR EXCAVATING MACHINE.

SPECIFICATION forming part of Letters Patent No. 287,763, dated October 30, 1883.

Application filed January 23, 1882. (No model.)

To all whom it may concern:

Be it known that I, HALE E. HAWK, of Kansas City, in the county of Jackson and State of Missouri, have invented a new and useful Improvement in Dredging and Excavating Machines; and I do hereby declare that the following is a full, clear, and exact description thereof, which will enable others skilled in the art to make and use the same, reference being had to the accompanying drawings, forming part of this specification, in which—

Figure 1 is a side elevation of the machine. Fig. 2 is a plan view of the same. Fig. 3 is a side view of the bucket, showing the devices for operating the cleaner. Fig. 4 is a rear elevation of the bucket. Fig. 5 is a transverse-sectional view of bucket-carrier and truss-frames. Fig. 6 is a front elevation of the rotary belt-conveyer. Fig. 7 is a detail view of the attachment holding the material-conveyer to the shaft.

The object of my invention is to construct a dredging and excavating machine which shall be capable, upon land or in submarine operations, of performing a great range of work, and in its mode of operation is designed to reach material at various angles with great rapidity and economy of labor, and at the same time to be wholly under control of one person from one given point upon the machine or carriage.

In the drawings, A represents a platform rotating upon a track upon a boat or carriage.

B represents a bridge-frame bolted to and supported by the platform A, and having pillow-block C and box a, on which rests the oscillating truss-frame of the excavating machine.

D is a timber bolted to bridge-frame B, on which main cross-line shaft b is supported.

E is the oscillating truss-frame, having girders c c, making part of the frame-work.

F is the sliding carriage for raising and lowering the bucket-carrier frame, extending part way within the truss-frame, and upon which driving-shaft d is journaled.

G G are guides on the truss-frame E, on which the sliding carriage F rests, and by means of gibbs e e on said carriage a sliding movement along the truss-frame is permitted.

H is a timber on the inner side of the truss-frame E, to receive a track, i.

I represents the bucket-carrier frame, having main beams K K, which are attached at one end to the sliding carriage, parallel track-rails f f, cross-arms g g, and girders U U. (See Fig. 5.)

k k are inclines upon the ends of the track-rails f f of the bucket-carrier frame I, to receive the travelers n, attached to the buckets when passing from one track to another.

l l are a series of wheels on main beams K K, which rest on tracks i i on timber H, and support the lower part of the bucket-carrier frame.

L L are rectangular wheels placed at opposite ends of the excavator on shafts d and m, by which they are rotated, and receive the connecting-links w w, for operating the chain of buckets.

N N are the excavator-buckets, having sides o o, (see Fig. 3,) face p, and swinging back r.

s is a stop on the bucket, being a continuation of face p.

t is a tripping-lever pivoted at a' upon the side o of the bucket N, and connected by pitman u to crank v for operating the swinging back of the excavator-bucket.

d' is a flange formed by extending the sides of the bucket past the ends. w w are a series of connecting-links on the chain of buckets, which are secured to said buckets at y, and also to the shaft x, which latter receives the travelers n.

P P are extended arms forming part of and describing an oblique angle with carriage-frame F, and provided with brace-arm q and upsetting-arms R.

Attached to the upper end of the guides G is a flanged wheel, S, and shaft z.

T is a drum on shaft z between guides G G on the truss-frame. k' is a sheave on carriage-frame F. (See Fig. 2.)

V and W are transmitting-arms carrying counter-shaft S', and attached to shafts b and d on the bridge-frame and sliding carriage-frame, respectively.

l' is a wire rope fastened at the upper end of guides G G, whence it passes through sheave k' on the sliding carriage F, and thence around drum T.

e'' is a wire rope running from flanged wheel S, to which it is fastened, to sheave f'' on the bridge-frame, and thence to drum g'' on tim-

ber D of the bridge-frame, to which it is also fastened.

h' h' are belts on pulleys m' and Y, communicating motion to shaft S'.

5 i' i' are belts running from drum r' on shaft S' to pulley o' on shaft d.

B' is a guide-bar pivoted upon the rotary platform A, and slotted longitudinally to receive a guide-pin, t', on the truss-frame E.

10 C' is a drum on shaft w'', supported by timber D of the bridge-frame B.

v' is a wire rope fastened to truss-frame E at x', and running over sheave W' on the upper end of guide-bar B', thence around drum C' on the bridge-frame, thence to x' on the truss-frame—the point of connection.

15 D' D' are rotary belt-conveyers, the upper one attached to sliding carriage F at one end by means of pendent arms g' and shaft n'. c'' 20 is a plate on shaft n'. p' is a flanged cap fitting over plate c'' on shaft n' (see detail view, Fig. 7,) and supporting the belt-conveyer in lateral and vertical movement.

h'' is an endless belt on drums z' z', which runs 25 over V-shaped pulleys y' y', arranged within the conveyer. b'' is a cleaner on the rotary belt-conveyer.

a'' a'' (see Fig. 6) are cant-boards in the conveyer.

30 i'' is a lever for raising belt-tightener o'' against belt m'', operating drum C', and thereby elevating or depressing the machine.

k'' is a lever for raising belt-tightner p'' against belt n'', operating drum g'', upon which 35 rope e'' is fastened.

D'' is the main driving-shaft, connected with vertical shaft A' by the ordinary bevel-gear.

E'' is a shaft for rotating the platform A, and is provided with pulleys s'' t'' and cog-wheel v''.

40 F'' is a support upon the deck or carriage to receive the shaft E''.

t' t'' are reversing-levers operating to throw into connection open and cross bands on pulley s'' and t'' on shaft E'', which run upon similar pulleys on shaft D'', and rotate the platform A.

50 X is a bevel-gear on shaft b, connected by a like gear with the vertical shaft A', for the transmission of motion to the working parts of the machine.

In the construction of the machine I use the ordinary rotating platform moving upon a suitable track upon a vessel or carriage, and upon which the bridge-frame B is built. 55 Through the center of the rotary platform, and acting independently thereof, shaft A' passes. The shaft A' is provided with suitable bevel-gear-actuating gear X, which latter gear is arranged upon main cross-line shaft b, and shaft

60 A' is connected by similar gearing with the driving-shaft D'' from the engine. The framework B upon the platform is composed of timber D, on which main cross-line shaft b is supported, and pillow-block C, which latter 65 is provided with box a to receive the journals arranged upon the truss-frame of the excavator.

Within the truss-frame E, and parallel in relation to the same, is arranged a separate sliding carriage, F, extending a suitable length 70 within said frame, to support the shaft d, and moving along said frame in guides G G. The bucket-carrier frame I is also arranged to move in a parallel relation to and within the truss-frame. The main beams K K of it are attached at 75 their upper ends to the sliding carriage F, the lower ends of said beams having a series of wheels, l l, which move on tracks i i on timber H on the truss-frame, and by means of which mechanism the bucket-carrier frame is enabled 80 to be extended beyond the truss-frame, and to such a depth as would be necessary to reach the material to be excavated. The sliding carriage is operated, in connection with the bucket-carrier frame, to which the latter is attached, 85 in the direction of the length of said frame by a wire rope, l', which rope is secured to the upper end of the guides G G, and passes through sheave k' on the sliding carriage, and thence to drum T on shaft z on said guides, to 90 which it is fastened, and when the sliding carriage is released by rope l' it moves downward by its own weight.

Located upon the sliding carriage, and also upon the extreme ends of the main beams K 95 K of the bucket-carrier frame, respectively, are the shafts d and m, upon which shafts the rectangular wheels L L are placed. The wheels L L are operated by means of pulley o', upon which is the band i' i', running to pulley r', 100 and band h' to pulley m', with the main cross-line shaft of the machine.

The bucket-carrier frame I is composed of the cross-arms g, having curved ends e', (see Fig. 5,) and rails f and beams K K, to which 105 beams the arms g are bolted. The girders U are arranged to support the beams K K in a uniform relation to and within the truss-frame. The curved portions e' of arms g are designed to permit the travelers upon the chain of buckets to pass exteriorly to the said arms and to the bucket-carrier frame in their upward and 110 downward movement on track-rails f.

In the construction of my excavator-buckets the sides o of the same are arranged to permit a face-plate, p, to be riveted thereto and extend partly around the point of the bucket, thus forming a stop for swinging back r. The 115 swinging plate r forms an independent back 120 of the bucket, and is secured at b' by casting g'' to a shaft, c', which is arranged across the bucket. When the bucket is in the act of filling, the material throws the swinging back r to the rear and against stop s on the bucket. 125

Forming part of the sides of the buckets o are flanges d' d', which protect the tripping-levers in passing between the rectangular wheels L L on the shaft d on the sliding carriage, and also from contact with the material when excavating, and project over and at right angles to the ends.

Actuating shaft c' on the bucket are a series of levers t, u, and v, which act to throw

automatically the swinging back r forward when said levers t meet the upsetting-arms R on the sliding carriage, thus allowing back r to perform two offices—first, when filling and thrown back against the stop by the material, to act as the back of the bucket, and also as a cleaner for removing the contents. In place of the pitman u and the connecting-levers, I may use a double bell-crank lever to accomplish the same purposes.

The endless chain of buckets have the links w secured to each other at x by a common bolt, and also to the bearings for travelers n n on the buckets, and to the buckets at y . Extended arms P P , forming part of the carriage-frame F , extend obliquely downward therefrom, and support a cross-brace, q , obliquely above which one or more upsetting devices R R are secured, which meet the tripping-levers t t on the buckets in their rotation on wheels L L , and thereby said bucket-bottoms are automatically upset at the discharging-point.

Two pendent arms, g g , secured rigidly to the sliding-carriage frame F , carry a horizontal shaft, n' , upon which shaft a plate, c' , is fastened, and provided with a movable flanged cap, p' . Upon the cap p' the end of the rotary belt-conveyer rests and follows each relative movement of the truss and carriage frames.

The rotary belt-conveyer D' is composed of parallel sides, as ordinarily constructed, and is provided with two or more ordinary pulleys, z z' , over which the belt h'' is driven. A series of V-shaped pulleys, y' , are located between and in line with pulley z' within the conveyer. a'' a'' (see Fig. 6) are cant-boards, under the edge of which the belt h'' passes. Now, when the material is emptied from the excavator-buckets, it falls directly upon the belt, which accommodates itself to the inclines d'' d'' on the V-shaped pulleys, and conveys the materials to any desired point. At the point where belt h'' passes over pulley z' , I arrange a device, b'' , to clean said belt from the accumulation of the material, and operate the belt by means of a belt arranged upon shaft d , and also upon a shaft on pulley z' on the conveyer. The movements of the truss frame in elevating and depressing the same are controlled by the guide-bar B' , which I have constructed to carry the rope v' , which passes over the sheave W' and around drum C' , thence to the point of connection at x' on the truss-frame, by which the power from the main shaft may be communicated. In place of the latter arrangement I may use a rotary device upon the truss-frame and suitable bevel-gear on the guide-bar, to accomplish the desired end.

The transmitting-arms V and W , transmitting power from shaft b on the bridge-frame to shaft d on the sliding carriage, are suitably connected therewith in a vertical relation, and are connected together by the shaft S' , which supports the counter-pulleys Y and r' for receiving the belts h i' . The transmitting-arms are so arranged that the free joint

supporting the counter-pulley Y permits the elevation and depression of the truss-frame, and at the same time a lateral movement of the sliding carriage, thus forming a self-adjusting power-conveyer.

In the operation of the machine the controlling-levers are arranged at one point on the vessel or carriage, whereby greater efficiency is attained in directing the various movements of the same. The levers l l' operate by means of belt-tighteners arranged on the same to transmit motion through cross and loose belts on pulleys s'' and t' , and similar pulleys on shaft D'' , to the shaft E'' , operating cog-wheel v'' , which engages with a toothed segment or rack on the rotating carriage or platform, whereby the rotary movement of the platform upon its track is attained while the operative parts of the machine are in full operation and controlled in independent or combined movement. The direction in which the material to be excavated lies being ascertained, and the excavator rotated upon its track to the desired point, lever i'' is operated to throw belt-tightener a'' against belt m'' , driving drum C' , operating rope v' , which is secured at x on the truss-frame, by which the truss-frame is elevated or depressed to such an angle as to permit the excavator-buckets to enter the material, the guide-bar B' , carrying the rope v' , regulating the movement and adapting itself by its longitudinal slot to the varying angles of said frame.

In the operation of a rotary chain of excavator-buckets heretofore, said buckets have been arranged to decrease leverage, and consequently the strain and power required to operate the buckets. The object, however, in the arrangement of my buckets is to prevent the friction and adhesion of the buckets to the material when entering the same, wherein the greatest amount of resistance to the rotation of the buckets is discovered, and which results from the entry and exit of the whole front side of the bucket in the same curved plane. In the construction of my excavator-buckets, however, I form the fronts and backs in curves described from two opposite centers intersecting in one direction, or at the point of the bucket, so that when said bucket enters the material it presents only the cutting-edge of the bucket to the soil, thereby loosening the same by a prying movement, and filling the bucket more readily without contact of the front side, but only the edge, thus decreasing the power ordinarily required to rotate the chain.

In connecting my buckets with the endless chain, I pivot said buckets between the centers of curvature and to the joints of the links in said chain, using the same pivot or not, as required, the pivotal point being near the mouth of the bucket. This arrangement permits the cutting-edge of the bucket to be thrown beyond the rectangular wheel in excavating, thus preventing the contact of any portion of the rotating parts of the bucket-carrier frame

with the material. The buckets, which are constantly working upon the bucket-carrier frame in endless movement, are driven immediately by the bands h' and i' on pulleys n' , o' , 5 and m' , enabling said buckets to reach the material by the extension of the bucket-carrier frame, this being accomplished by the action of a brake on the platform A , which releases the drum g'' , carrying rope e'' , which 10 rope passes through sheave f'' on the truss-frame to pulley S on the sliding carriage. At the same time rope l' , which is oppositely wound upon drum T , (which drum is fixed to and moves simultaneously with pulley S ,) is 15 unwound through sheave k' , the sliding-carriage and bucket-carrier frames moving along the truss-frame by their combined weight to the required distance. In the raising of the bucket-carrier and sliding-carriage frames lever k'' is operated to throw the belt-tightener p against belt n'' , setting in motion drum g'' and winding rope e'' , and through pulleys S and drum T the rope l' , by means of which the result is attained. In the extension of the 20 sliding carriage the transmitting-arms V and W follow each longitudinal movement of said frame, and at the same time accommodate themselves to the oscillations of the truss-frame.

30 Having fully described my invention, what I now claim, and desire to secure by Letters Patent, is—

1 . In combination with an oscillating truss-frame in an excavating or dredging machine, 35 and a sliding carriage arranged in suitable guides within said frame, a bucket-carrier frame attached to said carriage and moving upon a suitable trackway within the truss-frame, and adapted to be extended beyond and 40 in a corresponding direction with said frame, as described.

2 . In combination with an oscillating frame of an excavating and dredging machine, a longitudinally-slotted guide-bar pivoted at its 45 lower end to the supporting-carriage, and a pin attached to said oscillating frame and arranged to play in the slot in the guide-bar, as shown and described.

3 . In combination with an oscillating frame 50 of an excavating and dredging machine, a longitudinally-slotted guide-bar pivoted at its lower end to the supporting-carriage, and having a pin arranged to play in the slot in said guide-bar, which pin is attached to the oscillating frame, and a raising and lowering device attached to the said frame and operating in suitable guides upon the guide-bar, in connection with the driving-shaft upon the machine, substantially as set forth and described.

60 4 . In combination with a bucket-carrier frame for an excavating and dredging machine, having longitudinal supporting-beams and transverse girders attached thereto, the arms arranged at right angles to said beams, and in 65 connection therewith and supporting the track-rails in a parallel relation to each other, said

arms being arranged at an inclination toward each other from their point of attachment to said beams, as shown and described.

5 . An excavator-bucket provided with ends 70 which are constructed in a plane described from two opposite points of curvature intersecting in one direction or at the point of the bucket, and having suitable sides conforming to said ends, for the purpose specified. 75

6 . In combination with the bucket-carrier frame of an excavating and dredging machine, provided with oppositely-arranged wheels and an endless linked chain upon said wheels, an excavating-bucket of the form of meeting 80 curves, as described, pivoted longitudinally to said chain between the centers of curvature and at the gravitating-point of the bucket, for the purpose specified.

7 . An excavator-bucket provided with a 85 shaft for the operation of a cleaner therein, and operating mechanism therefor outside the ends of the bucket, and a flange attached to the side of the bucket and extending a suitable distance beyond and at right angles to the ends of the same, for the purpose specified.

8 . An excavator-bucket having a swinging back pivoted to the ends, and a tripping-lever attached to said pivot upon the exterior of the end of the bucket, and provided with one or more 95 jointed extensions of the same, which are pivoted to said bucket, for the purpose described.

9 . In combination with a rotary supporting-shaft located upon a dredging or excavating machine, and provided with a plate rigidly secured thereto, a material-conveyer having its pivotal end provided with a movable flanged cap engaging with the plate upon said shaft, for the purpose set forth.

10 . In combination with the sliding-carriage 105 frame of an excavating and dredging machine, having depending supports attached to said frame, and a rotary supporting-shaft attached to said supports, a plate secured to said shaft, and provided with a movable flanged cap, 110 which is adapted to fit over and engage with the plate on said shaft, and support the end of a material-conveyer, as shown and described.

11 . In combination with an oscillating truss-frame of an excavating and dredging machine, 115 provided with a bucket-carrier frame which is arranged to slide in suitable guides upon said truss-frame, the transmitting-arms, attached, respectively, to the driving-shaft upon the bridge-frame and to the driving-shaft 120 upon the bucket-carrier frame, and having their opposite ends independently connected together by a suitable shaft, whereby their lateral extension shall be permitted in the elevation and depression of the machine, as shown 125 and described.

12 . In combination with an oscillating truss-frame of an excavating and dredging machine, provided with a bucket-carrier frame which is arranged to slide in suitable guides 130 upon said truss-frame, the transmitting-arms, attached, respectively, to the driving-shaft

upon the bridge-frame and to the driving-shaft upon the bucket-carrier frame, and having the opposite ends independently connected together by a suitable shaft, and a pulley attached to said shaft, the operating-belts connected with the pulley upon the driving-shaft on the bridge-frame of the machine and the driving-shaft on the sliding-carriage frame, and also with the pulley attached to the shaft 10 on the independent ends of the transmitting-arms, as shown and described.

13. In combination with a rotary platform in an excavating and dredging machine, which is adapted by suitable frame-work to support 15 the truss and bucket-carrier frames, and the driving-shaft conveying power to and operat-

ing the said frames, the vertical shaft arranged centrally through and operating independently of the rotary platform, and provided with suitable bevel-gear which meshes with and operates the driving-shaft on the carriage-frame, and a suitable shaft connected therewith, and also with the engine, whereby the entire operation of the platform simultaneously with the machine may be effected in any direction, and 20 in an independent relation to the machine, as specified. 25
